UNITED STATES PATENT OFFICE.

CHARLES L. DAVIS, OF DETROIT, MICHIGAN, ASSIGNOR OF ONE-HALF TO HARRY W. FROST, OF DETROIT, MICHIGAN.

ELECTRIC VAPORIZER.

1,091,637.

Specification of Letters Patent. Patented Mar. 31, 1914.

Application filed May 9, 1913. Serial No. 766,580.

To all whom it may concern:

Be it known that I, CHARLES L. DAVIS, a citizen of the United States of America, residing at Detroit, in the county of Wayne 5 and State of Michigan, have invented certain new and useful Improvements in Electric Vaporizers, of which the following is a specification, reference being had therein to the accompanying drawings.

10 The invention relates to electric vaporizers more particularly designed for use in connection with explosion engines using kerosene or other liquid fuel of low volatility.

It is one of the objects of the invention to 15 obtain a construction which in operation will discharge only vapor, and in which the oil is quickly vaporized and in proportion to the demand.

With these objects in view the invention 20 comprises various features of construction as hereinafter set forth.

In the drawings: Figure 1 is a diagrammatic view showing the vaporizer when out of action; Fig. 2 is a similar view with the 25 vaporizer in operation; and Fig. 3 is a cross section on line $x-x$ of Fig. 2.

In the operation of explosion engines by kerosene or other relatively heavy liquid hydrocarbons, the chief difficulty experienced 30 is in obtaining an explosive mixture for starting. Various pre-heaters for the oil, electric and other constructions, have been employed, but these, while heating the oil and perhaps discharging the mixed oil and

35 vapor, have not proven efficient for the discharge of vapor alone. As a consequence, more or less of the liquid hydrocarbon is carried into the engine cylinder where it is carbonized, producing difficulties with the 40 igniter and other objectionable results.

With my improved construction, the difficulties are avoided—first, by holding the liquid back from the discharge nozzle by the pressure of the vapor generated; second, by 45 varying the heating surface exposed to the liquid to produce a corresponding variation in the quantity of vapor generated; and third, by preventing communication of heat to the body of liquid and in restricting the

50 amount of liquid in contact with the heater to increase its speed of operation and efficiency.

As shown, A is a suitable receptacle for the oil or other liquid to be vaporized, and 55 which is preferably maintained at a con-

stant head or hydrostatic level by suitable means (not shown).

B is the vapor discharge nozzle, which is preferably arranged with its discharge orifice approximately at the level of the liquid 60 in the receptacle A.

C is an electric heater within the nozzle B, arranged slightly below the discharge end thereof, but in a position to be normally immersed in the liquid. 65

D is a conduit connecting the receptacle A with the nozzle B at a point below the lower end of the heater C and preferably having a bend or trap E therein, preventing any thermo-siphon circulation of the liquid. 70

The proportion of the parts just described is such that the rate of vapor generation produced by the heater C when immersed in the liquid is greater than that which can be discharged through the restricted orifice F 75 under the hydrostatic pressure of the liquid in the receptacle A. As a consequence, the initial operation of the heater will develop a vapor or gaseous pressure within the nozzle, which will drive back the liquid against the 80 hydrostatic pressure until a portion of the heating surface is exposed to the vapor only. In the continued generation the vapor evolved by the boiling liquid will be compelled to pass the exposed portion of the 85 heating surface which will produce a super-heating, discharging from the nozzle a gas that will not readily condense. This will commingle with air in any suitable air mixing chamber (not shown) such as the induction conduit of the engine. 90

Another effect that is automatically produced by the construction above described is the regulation of the heat in accordance with the discharge of the vapor. As is well 95 known, the electrical resistance of most metallic resistors increases with increase in temperature. It is also a fact that the heat generated in a resistor may be much more rapidly dissipated when in contact with a 100 liquid than by the contact of a gas. Thus initially the heater C being completely immersed in a liquid and cooled thereby will be of a lower electrical resistance than when the liquid is driven back and a portion of 105 the surface is exposed only to vapor. This will permit a larger current volume to pass through the resistor at the start with a corresponding heat generation, while after a portion of the surface is exposed to vapor, 110

the increase in temperature will increase the resistance and diminish the current. This, in turn, will diminish the heat generation, which will lessen the rate of vapor generation, and consequently the amount of the heater exposed to the liquid will be automatically regulated to the amount of vapor discharged from the nozzle.

In the specific construction of the electric heater, I preferably employ a naked coil G arranged within a bifurcated metallic member H, preferably formed by a tube having opposite side portions thereof cut away. One terminal of the coil G is electrically connected to the outer end of the tube H, while the other terminal is connected to a central rod I passing out through the tube and insulated therefrom. The rod I may be attached to one of the terminals of the electric generator, while the tube H may be grounded. This forms a convenient construction which is readily insertible in either the induction conduit for the engine, in the nozzle of the carburetor, or in any other place where it is desired to place the vaporizer.

What I claim as my invention is:

1. A vaporizer, comprising a vapor discharge nozzle, means for establishing a hydrostatic level of the liquid to be vaporized below the discharge end of said nozzle, and a heater for the liquid within said nozzle, having a rate of vapor generation in excess of the rate of vapor discharge from said nozzle under the hydrostatic pressure of the liquid, whereby said liquid is driven back from the nozzle by vapor pressure.

2. A vaporizer, comprising a vapor discharge nozzle, a supply connection for the liquid to be vaporized having a normal hydrostatic level below the discharge orifice of said nozzle, and a heater immersed in said liquid when at normal level having a rate of vapor generation in excess of the rate of vapor discharge under normal hydrostatic pressure, sufficient to drive back the liquid and to expose a portion of the heating surface to vapor only.

3. A vaporizer, comprising a vapor discharge nozzle, a supply connection for the liquid to be vaporized, having a normal hydrostatic level below the discharge orifice of said nozzle, and a heater having its surface exposed to liquid contact when at normal level and of a vapor generating capacity in excess of the rate of vapor discharge under normal hydrostatic pressure sufficient to

drive back the liquid from a portion of the heating surface and exposing the same to vapor only.

4. A vaporizer, comprising a vapor discharge nozzle, a supply connection for the liquid to be vaporized having a normal hydrostatic level below the discharge orifice of said nozzle, and an electric heater having its surface exposed to the liquid within said nozzle, the parts being so organized that the heat generated by said heater is regulated by a variable exposure of the heating surface of the same to the liquid and vapor.

5. A vaporizer, comprising a vapor discharging nozzle, means for supplying the liquid to be vaporized under a predetermined pressure thereto, and a heater for the liquid within said nozzle having a rate of vapor generation in excess of the rate of vapor discharge from said nozzle under the pressure upon the liquid, whereby said liquid is driven back in the nozzle by vapor pressure.

6. A vaporizer, comprising a vapor discharge nozzle, a supply connection for liquid to be vaporized having a normal hydrostatic level, and a heater immersed in said liquid when at normal level having a rate of vapor generation in excess of the rate of vapor discharge under the hydrostatic pressure, sufficient to drive back the liquid and expose a portion of the heating surface to vapor only.

7. A vaporizer, comprising a vapor discharge nozzle, means for supplying liquid to be vaporized under a predetermined pressure thereto, and a heater for the liquid within said nozzle, said nozzle having its discharge restricted to a rate less than the rate of vapor generation, whereby the liquid is driven back in the nozzle by vapor pressure.

8. A vaporizer, comprising a vapor discharge nozzle, means for supplying liquid to be vaporized under a predetermined pressure, and a heater for the liquid within said nozzle, the rate of vapor generation being proportioned relative to the rate of vapor discharge, whereby the liquid is driven back in the nozzle by the vapor pressure arising from the difference in rate of the vapor generation and discharge.

In testimony whereof I affix my signature in presence of two witnesses.

CHARLES L. DAVIS.
